UNITED STATES PATENT OFFICE

2,434,206

FOLDED NAPKIN DISPENSER

Robert T. Frieders, Menasha, Wis., assignor to
 Marathon Corporation, Rothschild, Wis., a corporation of Wisconsin

Application August 8, 1946, Serial No. 689,265

2 Claims. (Cl. 312—62)

1

This invention relates to improvements in dispensing devices of that type in which a closed container is provided for holding folded paper napkins, or like articles, to protect them against soiling previous to use, and to permit the withdrawal of but a single article and at the same time to prevent waste of the articles.

One of the objects of the invention is to provide a container of the type disclosed in Patent No. 2,138,692 comprising a casing divided transversely at an intermediate part into two complementary sections, which are hinged together so that the casing can be easily opened and closed for loading the same, the two sections being adapted to form opposite receptacles to receive respectively stacks of the articles, with the two stacks separated by an intervening space, in which is mounted pressure exerting mechanism adapted to press the stacks toward the end walls of their respective sections so that individual articles can be dispensed through openings in the end walls of the sections when the two sections are closed. An object of the invention is to provide a means whereby the spring-urged bar which links the pusher plate to the base of the dispenser may, when the dispenser is held open, be moved in either direction on its hinges.

In the dispenser referred to in Patent No. 2,138,692, a plate is riveted to the bottom of each dispenser section and each such plate is provided with an integral finger which is adapted to extend into the adjacent section and to engage the socket portion of the link bar in the adjacent section when the sections of the dispenser are swung open thereby retracting the pusher plates to a position perpendicular to the dispenser faces of the dispenser. With this arrangement if the dispenser sections are held open and the pusher plates and link bars are forced toward the respective dispensing faces, there is a tendency to break off the integral fingers mentioned above.

To overcome this difficulty, I have used a similar construction of the dispenser as described in the above-mentioned patent but have eliminated the integral fingers on the base plates and instead of having a coil spring on the pintle to urge the link bars outward I have provided two coil springs on the pintle, one to urge each link bar. One end of the coil spring is affixed to the plate which is riveted to the bottom of one of the dispenser sections and the other end affixed to the link bar in the adjacent section. When the section of the dispensers are opened, the springs urge the link bars to the position perpendicular to the dispensing faces of the dispenser; and

2

when the dispenser is closed, the springs urge the link bars toward the respective dispensing faces. When the dispenser is held open, the pusher plates and link bars may be forced in either direction without danger of any of the parts being broken.

The invention is described in detail herein-after, pointed out in the appended claims, and illustrated by the accompanying drawings.

10 In the accompanying drawings, in which similar reference characters designate corresponding parts

Figure 1 is a perspective view of the dispenser,
 Figure 2 is a sectional view of the dispenser

15 taken on lines 2—2 of Figure 1,

Figure 3 is a plan view of the dispenser in opened position,

Figure 4 is a perspective view of the opened dispenser,

20 Figure 5 is a side view of the fully opened dispenser,

Figure 5—A is an enlarged vertical sectional view of the hinge mechanism shown in Figure 5,

Figure 6 is a side view of the partially closed 25 dispenser, and

Figure 6—A is an enlarged vertical sectional view of the hinge mechanism shown in Figure 6.

Referring to the drawings, the dispenser comprises two complementary sections 1 and 2 hinged 30 together by pintle 60 so as to be swingable from the closed position shown in Figure 1 to the fully opened position shown in Figure 4. Section 1 consists of a top wall 10, side walls 9 and 14, and a bottom wall 30. Section 2 similarly consists of a top wall 12, side walls 8 and 15, and a bottom wall 31. Each of the sections 1 and 2 is provided with a front face plate 20 having an upper portion 22 protruding inwardly of the sections 1 and 2 as shown in Figure 2. Face plate 20 is provided 35 with an oval shaped opening through which the folded napkins A may be withdrawn from the dispenser.

Section 1 is provided with a flange portion 13 extending beyond the edge portions of the top wall 10 and side walls 9 and 14. The flange portion 13 is adapted to overlap the edge portions of the top wall 12 and side walls 8 and 15 of section 2 as shown in Figures 1 and 2 so as to securely close the sections 1 and 2. A tongue portion 19 (see Figure 6) is provided adjacent one edge of section 2 which engages a complementary slot 18 in flange 13 of section 1, so as to releasably lock the sections together. A pair of guide plates 33 are provided in each dispenser section for supporting and guiding the bottom edges of the nap-

kins as they are pushed toward the dispensing opening. Plates 81 are provided in the rear of each dispenser section for retaining the rear of each stack of napkins positioned therein.

A plate 40a is riveted to the bottom 31 of section 2 as shown in Figure 2. Similarly a plate 40a is riveted to the bottom 30 of section 1. Plates 40a are provided with interfitting knuckle portions 71 and 72 which are retained by pintle 70 for permitting swinging of the sections 1 and 2 on said pintle.

Each section 1 and 2 is provided with a pusher plate 40 which is actuated by spring urged link bar 43 for exerting pressure upon the rear of a stack of napkins A placed in each section as shown in Figure 2.

Wing portions 42b are stamped out of each pusher plate and are provided with openings for hingedly receiving pins 44 provided at one end of the link bar 43. The other end of each link bar adjacent pintle 70 is provided with cut out portions 52 complementary with socket portions 50 provided on plates 40a. The link bars are also provided with hinge knuckle portions 43a for receiving pintle 70 so as to be swingable thereon.

Two springs 60 are coiled on pintle 70 for normally urging each link bar forwardly toward the dispensing opening. One end 66 of the spring extends through an opening 65 in the link bar and the other end 61 of the spring projects into the socket portion 50 in the opposed section as shown in Figures 2 and 6-A. When the sections 1 and 2 of the dispenser are opened partially as in Figure 6, or fully as in Figures 4 and 5, the sockets 50 will engage the ends 61 of the spring and urge the link bars pivoted on pintle 70 to assume an upright back-to-back position shown in Figures 4 and 5. Each of the link bars and pusher plates 40 pivoted thereon can be manually pushed toward either section 1 or 2 as shown by the dotted lines in Figure 5. Thus any accidental pushing of the pusher plates after the sections 1 and 2 are opened will not cause any damage to the link bars as often occurred in the construction disclosed in Patent No. 2,138,692.

The bottom of each section is provided with rubber legs 21 for supporting the dispenser upon any desired supporting surface without scratching or marring the same.

In using the dispenser, the sections 1 and 2 are swung open by manually releasing tongue 19 from slot 18 so that the sections assume the position shown in Figure 4, with the pusher plates 40 retracted out of the sections and in back-to-back relation. A stack of napkins is then placed in each section with the grasping tabs A properly aligned so as to be presented at the dispensing opening in each of the front face plates. The sections 1 and 2 are then swung together and locked by the engagement of tongue 19 in slot 18 in the position shown in Figure 1. As the individual napkins are removed from the dispensing slot the pusher will urge forwardly the remaining napkins in proper position for dispensing purposes.

The construction of the dispenser as herein described thus provides a dispenser having two complemental hinged sections, each section adapted to contain a stack of napkins which are urged forward toward the dispensing slot by a pusher plate. When the sections are swung open the construction of the dispenser provides automatic means for retracting the pusher plates from the sections thereby permitting them to be refilled with a fresh supply of napkins. When

the sections are closed upon the separated stacks of napkins the pusher plates are automatically actuated so as to urge the napkins toward the dispensing opening for positioning the napkins in proper position for withdrawal from the dispenser.

Numerous changes and modifications may be made in the details of the construction herein described and it is intended to cover such modifications within the scope of the appended claims except as they may be limited by the prior art.

I claim:

1. A dispenser for folded napkins and the like comprising two complemental sections, each section having a top, bottom, sides and a front face panel, said front face panel being provided with a dispensing opening, a hinge connection between the bottoms of the complemental sections including a pintle, whereby the sections may be closed upon separated stacks of napkins arranged in each section to abut the said respective front face panels so as to be dispensed through said dispensing openings, means for retaining the sections in closed relation, a link bar in each section hinged at one end upon said pintle, a pair of coiled springs on said pintle for urging each of said link bars outwardly, pusher plates hinged to the other end of said link bars for urging the separated stacks toward the respective front face panels when the said sections are closed, and a plate affixed to the bottom of each section, said plate being provided with a socket portion adjacent said pintle, one end of each of said springs being affixed to one of said link bars and the other end of each of said springs being engaged in the socket portion of the opposed section and being adapted for automatically retracting said link bars and pusher plates from each of said sections when the sections are swung open.

2. A dispenser for folded napkins and the like comprising two complemental sections, each section having a top, bottom, sides and a front face panel, said front face panel being provided with a dispensing opening, a hinge connection between the bottoms of the complemental sections including a pintle, whereby the sections may be closed upon separated stacks of napkins arranged in each section to abut the said respective front face panels so as to be dispensed through said dispensing openings, means for retaining the sections in closed relation, a link bar in each section hinged at one end upon said pintle, a pair of coiled springs on said pintle for urging each of said link bars outwardly, pusher plates hinged to the other end of said link bars for urging the separated stacks toward the respective front face panels when the said sections are closed, a socket portion in the bottom of each section adjacent said pintle, one end of each of said springs being affixed to one of said link bars and the other end of each of said springs being engaged in the socket portion of the opposed section and being adapted for automatically retracting said link bars and pusher plates from each of said sections when the sections are swung open.
